UNITED STATES PATENT OFFICE.

WILLIAM W. SLACK, OF TRENTON, NEW JERSEY.

DESIGN FOR A LID FOR A WATER-CLOSET TANK.

54,136.

Specification for Design.

Patented Nov. 4, 1919.

Application filed April 27, 1916. Serial No. 94,084. Term of patent 14 years.

To all whom it may concern:

Be it known that I, WILLIAM W. SLACK, a citizen of the United States, residing at Trenton, in the county of Mercer and State of New Jersey, have invented a new, original, and ornamental Design for a Lid for Water-Closet Tanks, of which the following is a specification, reference being had to the accompanying drawing, forming part thereof.

The figure is a perspective view of a lid for a water-closet tank, showing my new design.

I claim:

The ornamental design for a lid for a water-closet tank, as shown.

WILLIAM W. SLACK.
